SMOKER'S DEVICE

Adolph H. Smeby, Los Angeles, Calif., assignor to
Hoepli & Co., New York, N. Y., a copartnership

Application October 15, 1936, Serial No. 105,770

6 Claims. (Cl. 131—232)

This invention relates to smokers' devices and is herein illustrated in the form of a cigar or cigarette cutter having parts adapted to remove debris from the bowl of a smoker's pipe and as forming part of an ashtray.

Hitherto, when a cigarette was discarded by a smoker, a careful smoker stamped the lighted end several times on an ashtray to extinguish it, while a careless smoker unwilling to take that trouble merely tossed it into the ashtray and let it smolder and smoke. Moreover, no satisfactory cigar cutter has yet been devised suitable to mount upon the usual ashtray, and no convenient device for removing the debris from the bowl of a smoker's pipe has been devised which is suitable either to carry in the pocket or to mount upon an ash tray.

According to the present invention the foregoing and other difficulties and objections are overcome, and a device is provided which may be carried in the pocket as a pocket cigar cutter, or which is well adapted to form part of an ashtray to serve as a smoker's article.

In the form shown the cutting device is formed by two resilient plates cut away where they face one another to form a nearly circular opening with inwardly projecting teeth. The plates are shown as parts of a single strip of sheet steel, fast, at its middle, to the center of the tray, and with resilient stretches between the tray and the blades on which the blades turn as they yield and which also yield to permit the backs of the blades to enter the bowl of a smoker's pipe.

The yielding stretches of the resilient strip 35 yieldingly press the back of the blades against the sides of the bowl to aid in cleaning out its irregularities.

While the structure holding the blades is described as fast to the ashtray it is shown as bolted thereto, thus permitting the trays and blades to be shipped knocked down and set up at the retail store where sold.

The openings of the blades are shown as provided with biting teeth instead of sharpened cutting edges. It is found that such teeth bite off the end of a cigar effectively and hold it without slipping and also bite a cigarette in two and disintegrate the small end cut off it so that it burns up rather rapidly instead of smoldering.

Other features and advantages will hereinafter appear.

In the accompanying drawing:

Figure 1 is a perspective view of the device forming part of an ashtray.

Figure 2 is an edge view of the cutting blades.

Figure 3 is a plan view of the same.

Figure 4 shows the device cleaning out the bowl of a smoker's pipe.

Figure 5 is an enlarged side view of the cutting blades.

In the form shown an ashtray 10, which may be of stamped metal has a boss 11 stamped upwardly at the center of its base 12. A flat strip 13 of resilient suitable gauge steel is shown as 10 held to the boss 11 by the head 14 of a bolt 15 which is drawn down against the strip by a nut 16 threaded on under the boss 11.

The strip 13 is shown as bent straight up at each side at 17 near the edge of the boss 11 forming a resilient or spring stretch 18 at each side.

Further up, at 19 each stretch 18 is shown as given a quarter turn to form a pair of flat portions 20 and 21 which overlap from near the turns 19 to their tops. The outsides of the plates 20 and 21 are shown as each shaped in a curve to approximately fit one half of the inside of a typical smoker's pipe, and then each outside bends down slightly to where the outside edges of the overlapping plates cross, thus making a smooth 25 curve when the plates are sprung together around their resilient stretches 18 to fit the inside base of pipe 22, see Figure 4. Thus the plates fit a large variety of pipe bowls and yieldingly slip over irregularities in the bowls.

For cutting off cigars or cigarettes, the overlapping plates are each cut away to form a row of teeth 23, so that all the teeth together form approximately a circle, when the plates 20 and 21 stand in their normal position.

To cut off a cigar end the end of the cigar is held by one hand in the circle of teeth 23, while the other hand, usually by thumb and finger, closes the plates 20 and 21, on each other. As the flat portions of the plates slide over each other, turning on their resilient stretches 18, the teeth 23 press into, slide into and bite into the cigar, and are found to satisfactorily bite it off even though they need be no sharper than the stamping operation leaves them when they are made.

Similarly the teeth bite off and disintegrate a short piece of a cigarette so that the burned end, if still alight quickly burns up.

In the form shown the teeth 23 form a circle 50 which is substantially concentric with the curve of the outer edge, and the left hand plate 21 is shown in front of the right hand plate 20, with the result that a right handed man in cutting a cigar tends to press the flat portion 21 against 55

the flat portion 20 and thus cut it more smoothly and firmly.

Having thus described certain embodiments of the invention, what is claimed is:

- 5 1. A smoker's device formed from a single sheet of metal turned up to form flat portions having facing cutting edges and adjacent guide faces lying against each other, and outside edges shaped to fit the interior of the bowl of a smoker's pipe
- 10 2. A smoker's device including a plate having one nearly semi-circular cutting edge and an opposite edge approximately conforming to the interior curve of the side of the bowl of a smoker's pipe, a correspondingly formed opposing plate, and a resilient means normally holding the cutting edges in cutting position but permitting the plates to slide upon one another to fit a pipe or to cut a cigarette or cigar.
- 15 3. A smoker's device including a plate thin enough to slip between the two parts of a match box and having one nearly semi-circular cutting edge and an opposite edge approximately conforming to the interior curve of the side of the bowl of a smoker's pipe, a correspondingly formed opposing plate, and a resilient means normally holding the cutting edges in cutting position but permitting the plates to slide upon one another to fit a pipe or to cut a cigarette or cigar.
- 20 4. A smoker's device including a plate having one nearly semi-circular cutting edge and an op-
- 5 5. A smoker's device including a plate thin enough to slip between the two parts of a match box and having one nearly semi-circular cutting edge and an opposite edge approximately conforming to the interior curve of the side of the bowl of a smoker's pipe, a correspondingly formed opposing plate, an ashtray, and a resilient means carrying the plates and fast to the ashtray and normally holding the cutting edges in cutting position but permitting the plates to slide upon one another to fit a pipe or to cut a cigarette or cigar.
- 10 6. A smoker's device including a plate thin enough to slip between the two parts of a match box and having one nearly semi-circular cutting edge and an opposite edge approximately conforming to the interior curve of the side of the bowl of a smoker's pipe, a correspondingly formed opposing plate, an ashtray, and a resilient means carrying the plates and fast to the ashtray and normally holding the cutting edges in cutting position but permitting the plates to slide upon one another to fit a pipe or to cut a cigarette or cigar.
- 15 7. A smoker's device formed from a single sheet of metal turned up to form flat portions having facing cutting edges and adjacent guides faces lying against each other, outside edges shaped to fit the interior of the bowl of a smoker's pipe to remove waste by turning the pipe, a flat spring section connecting the turned up portions, and a tray to which the spring section is held.
- 20 8. A smoker's device including a plate having one nearly semi-circular cutting edge and an op-
- 25 9. A smoker's device including a plate having one nearly semi-circular cutting edge and an op-
- 30 10. A smoker's device including a plate having one nearly semi-circular cutting edge and an op-
